FREDERICK W. BEARDSLEY, OF DRUMMONDVILLE, QUEBEC, CANADA, ASSIGNOR TO
CELANESE CORPORATION OF AMERICA, A CORPORATION OF DELAWARE

AUTOMATIC STOP FOR KNITTING MACHINES

Application filed May 3, 1928. Serial No. 274,854.

This invention relates to a mechanism for automatically stopping the operation of a knitting machine, when through failure of any of the mechanism, the tension of the yarn exceeds a predetermined amount.

An object of my invention is to provide means for stopping the operation of a knitting machine, and particularly a warp knitting machine, when the tension of the yarn 10 that is being fed through the knitting guides becomes greater than normal, thus preventing the yarn from breaking.

A further object of my invention is to provide an adjustment that may be applied to 15 any standard warp knitting machine, without any alteration to the machine, and which, when once set, does not have to be adjusted every time the machine comes to a normal stop.

20 In the standard warp knitting machine, the yarn is fed from the warp beam to the knitting needles. If, through any cause whatsoever, such as trouble in the automatic gear box the warp beam fails to feed the yarn to 25 the knitting bars as fast as is required, or not at all, the knitting needles continue taking up the yarn and knit the same, and as a consequence, the tension of the yarn increases so 30 much that the yarn breaks over the width of the machine, thereby causing a considerable delay in resetting the knitting machine.

In accordance with my invention, I provide 35 an automatic stop mechanism, which stops the operation of the knitting machine when the tension of the yarn substantially exceeds normal. In one form of my invention I provide a lever having arms which just clear the tension bars in normal operation. When the 40 tension of the yarn increases, the tension bars press down on the lever arms, and the lever causes a catch to disengage, which permits a spring operating mechanism to cause the machine to stop operating.

45 Referring more particularly to the accompanying drawings:

Figure 1 is an elevation showing the mounting of the automatic stop mechanism on the frame of the warp knitting machine.

50 Figure 2 is a cross section along the line

2-2 of Figure 1, showing the stop device proper in detail.

Figure 3 is a plan view partly in section taken along line 3-3 of Figure 2.

The device may be applied to any standard 55 knitting machine. The ordinary bracket of the machine for carrying the fabric roller and operating rod is shown at 1 in Figure 1. Mounted on the bracket 1 is the standard 2, which provides a fulcrum for the operating 60 lever 3. One end of the lever 3 is provided with the arms 4 which are so set that they are just clear of the tension rods 5, when the rods are at the lowest point of their normal motion. The yarn to be knitted passes from the 65 warp beam (not shown) over the tension rod 5 to the knitting bars diagrammatically shown at 6^a, and transmit the effect of their tension by tending to depress the tension rods 5 and therefore the left side of the lever 3 as 70 shown in Figure 1.

Attached to the other end of the lever 3 is the rod 6, which is normally held down by the action of the small tension spring 7. The rod 6 is provided with a horizontal portion 8 75 at its bottom which passes under latch 9 pivoted at 10. The free end of the latch 9 normally holds the catch 11, which is pivoted at 11^a, against rotation. When in normal position, the catch 11 prevents the motion of the 80 loop 12, but when it is released by the lifting of the latch 9, it tends to move to the left, due to the action of the coil spring 13. Within this loop 12, there is placed the member 14 which is fixedly attached to the knitting machine operating rod 15, and which slides along the rod 16. One end of the spring 13 is fastened to the member 17, which is attached to the rod 16. 85

In operation, when the warp knitting machine is operating normally, the yarn passes from the warp beam over the tension rods 5 to the guide bar 6^a. However, if for any reason whatsoever, the warp beam has stopped supplying yarn to the knitting bars the 90 knitting needles will continue taking up the yarn, and thus produce a tension downward on the tension rods 5. Usually after about six motions of needle bar, the tension of the 95 yarn becomes so great that the tension rods 100

5 cause the left hand side of the lever 3 to become depressed, thus raising the right hand side of the lever 3, and consequently rod 6, which raises the catch 9. This releases the latch 11 and therefore permits the loop 12 to move to the left, due to the action of the spring 13, and the loop engages the member 14 and causes it, together with the operating rod 15, to move to the left which automatically stops operation of the whole warp knitting machine.

10 After the trouble that has caused the failure of the proper feeding of the yarn to the knitting bar has been remedied, the machine is reset by lifting the tension rods 5 and thus allowing the latch 9 to drop again into normal position, whereupon the loop 12 may be set again into operating position.

15 It will be seen that the construction of this device is very simple and that it can be easily applied to any warp knitting machine at very slight cost.

20 It is to be understood that the foregoing detailed description is given merely by way of illustration, and that many variations may be made therein without departing from the spirit of the invention.

25 Having described my invention, what I claim and desire to secure by Letters Patent is:

30 1. In a warp knitting machine for knitting yarns, the combination with a warp beam, the tension rods over which all of the yarns of the warps pass, and the needle bars, of means operated by the tension rods for automatically stopping the operation of the knitting machine when the yarns of the warps as a whole exert a predetermined tension on the tension rods.

35 2. In a warp knitting machine for knitting yarns, the combination with the warp beam, the tension rods over which all of the the yarns of the warps pass, and the needle bars, of means for stopping the operation 40 of the knitting machine, a lever mounted on the frame of the knitting machine, one end of such lever being operated by the tension rods when the yarns of the warps as a whole exert a predetermined tension thereon and a connection between the other end of the lever and the means for stopping the operation of the knitting machine.

45 3. In a warp knitting machine for knitting yarns, the combination with the warp beam, the tension rods over which all of the yarns of the warps pass, the needle bars, and the operating rod, of means tending to move the operating bar into a position for 50 stopping the operation of the knitting machines, means for preventing the movement of the operating bar and means operated by the tension rods when the yarns of the warps as a whole exert a predetermined tension 55 thereon for disengaging the means for pre-

venting the movement of the operating rod.

60 4. In a warp knitting machine having tension rods over which all the yarns of the warps pass, needle bars, and an operating rod, the combination of a loop, means attached to the operating rod and engaged by said loop, means tending to move the loop in a direction to cause the operating rod to stop the operation of the knitting machine, a latch tending to prevent the movement of the loop, 65 a lever operated by the tension rods and having a connection with said latch, whereby when a predetermined tension is exerted by the yarns of the warps as a whole on the tension rods, the latch is disengaged, thus permitting the operating rod to be moved and cause the operation of the knitting machine to cease.

70 In testimony whereof, I have hereunto subscribed my name.

75 FREDERICK W. BEARDSLEY.
